UNITED STATES PATENT OFFICE.

DARIUS BENHAM AND XENOPHON STOUTENBOROUGH, OF NEW YORK, N. Y.

DESIGN FOR A CRUMB-PAN.

SPECIFICATION forming part of Design No. 13,479, dated December 19, 1882.

Application filed May 12, 1882. Term of patent 14 years.

To all whom it may concern:

Be it known that we, DARIUS BENHAM and XENOPHON STOUTENBOROUGH, of the city and State of New York, have invented or produced 5 a new and ornamental Design for a Crumb-Pan, of which the following is a specification.

The design of this crumb-pan consists of a shell-shaped bottom part, *a*, having numerous corrugations radiating or diverging from the back portion and increasing in depth and width toward the front edge, and the general shape of such bottom is elliptical and dishing, similar to a scallop-shell. The upper part, *b*, of the crumb-pan is of a somewhat similar shape to 15 the lower part, only it is not as wide as the lower part, so as only to cover the back part of such crumb-pan. The said upper part has a curved front edge, and the back edges of the parts *a* and *b* are arcs of circles, and united so 20 as to give the general ornamental appearance of scallop-shells placed together, but with the upper one cut off upon a curved line about the middle of the shell, and with a thumb-hole at *d*, from which the corrugations diverge. The 25 edges where the sheet metal comes together

are corded in appearance. This design is very neat and artistic. The surface is to be further ornamented by paint, lacquer, or bronze.

Figure 1 in the drawings is a plan view, and Fig. 2 is a section at the line *x* *x*. 30

We claim as our invention—

1. The design of the shape and configuration of the sheet-metal crumb-pan, consisting in an elliptical and dishing bottom part, having diverging corrugations, increasing in depth 35 and width from the back to the front edge, and a similarly-shaped upper part partially covering the bottom part, as shown and described.

2. The design of the shape and configuration of the upper part of the crumb-pan, the 40 same consisting of an imitation of a part of a scallop-shell in sheet metal, with a thumb hole or opening, as described and represented.

Signed by us this 3d day of May, A. D. 1882.

DARIUS BENHAM.
XENOPHON STOUTENBOROUGH.
